DIGGING WHEEL DRIVE

Hubert Hollmann, Findlay, Ohio, assignor to The Buckeye Traction Ditcher Company, Findlay, Ohio, a corporation of Ohio

Application February 28, 1941, Serial No. 381,093

7 Claims. (Cl. 74—432)

This invention relates to excavating machines but more particularly to excavating machines provided with a digging wheel which is equipped with an annular series of buckets which successively dig into the ground as the machine advances, thereby forming a trench.

An object is to produce a new and improved drive for a digging wheel of the above character in which a gear engages the teeth on the side of the digging wheel and in which another member engages the inner surface of the wheel, the latter member being movable or rotatable independently of the movement of the gear so that these parts can move at relatively different rates of speed, thereby materially improving the operation of the machine and reducing friction and consequently wear of the parts.

Other objects and advantages of the invention will hereinafter appear and for purposes of illustration but not of limitation, an embodiment of the invention is shown on the accompanying drawings in which

Figure 1 is a side elevation of a digging wheel and its supporting frame, the traction machine and other parts being omitted;

Figure 2 is an enlarged fragmentary view partly in section showing a driving gear in engagement with teeth on the gear segment;

Figure 3 is an enlarged sectional view showing the driving gear assemblies associated with the digging wheel structure;

Figure 4 is a sectional view of a driving gear assembly; and

Figure 5 is a vertical sectional view substantially on the line 5—5 of Figure 4.

The illustrated embodiment of the invention comprises a digging wheel indicated at W which is suitably supported from a frame F by a support S and rollers R, the frame F being connected to a tractor or other suitable machine (not shown). The digging wheel has an annular series of excavating buckets B which, as the wheel rotates, dig into the earth and discharge their loads successively upon a conveyor C which carries the dirt laterally of the machine. As shown in Figure 3, the digging wheel consists of a pair of laterally spaced rim members 10 to the inner portion of which are riveted arcuate gear segments 11 which together form a complete ring, and formed on the segments 11 is a series of spaced teeth 12 which extend outwardly from the side of the segment. The segments 11 are shaped in the form of an inverted L in cross section with the flange 13 thereof overlapping the inner edge portion of the rim 10. It is understood that the

construction is the same on each side of the digging wheel. The buckets B overlap the spaced rims 10 and are suitably bolted or riveted in place. The above described construction is old in the art so that more detail description thereof is not considered necessary.

For imparting rotation to the digging wheel W, a shaft 14 has a sprocket wheel 15 secured to one end about which is trained a chain 16 which leads forwardly to the tractor. The shaft 14 is square in cross section and adjacent each of the rims 10 is a gear assembly generally indicated at G and since the gear assemblies are identical in construction, description of one is deemed sufficient. The gear assembly G comprises an elongate hub member 17 which is formed with an annular enlargement 18. Abutting against the outer face of the enlargement 18 is a gear ring 19 which is shouldered to fit over a portion of the enlargement. The gear teeth 20 on the outer edge of the ring 19 are engageable with the teeth 12 on the gear segments 11. A series of bolt and nut assemblies 21 secure the ring 19 in place. As shown, the inner face of the gear ring 19 substantially abuts against the outer face of the gear segments 11. The outer surface of the hub enlargement 18 is annular and fitting thereon for rotation thereon is a ring 22 which engages the inner surface of the gear segment 11, there being substantial area of contact between the ring 22 and the gear segment 11 as indicated on Figure 3. It will be manifest that lateral movement of the ring 22 in one direction is limited by the inner face of the gear ring 19. Lateral shifting movement of the ring 22 in the opposite direction is limited by a flange 23 which is integral with the hub enlargement 18 and projects outwardly therefrom.

It will be manifest that in operation the relative speed between the gear ring or pinion 19 and the ring 22 are different. Heretofore considerable difficulty has been occasioned where the part which engaged the gear segment rotated or moved at the same rate of speed as the pinion which engaged the teeth on the arcuate segments 11. Excessive wear would take place in that region because of the sliding of the part to compensate for the difference in speed. In the above described construction, it will be manifest that such difficulties are overcome because the ring 22 can move at one rate of speed while the gear or pinion 19 can move at a different rate of speed. In this manner not only is the wear of the parts materially reduced and the troubles occasioned by break down and replacement reduced, but in

addition, the digging wheel is enabled to operate more smoothly and satisfactorily.

It is to be understood that numerous changes in details of construction, arrangement and operation may be effected without departing from the spirit of the invention especially as defined in the appended claims.

What I claim is:

1. A driving gear assembly for a digging wheel comprising a hub member, an annular enlargement on said hub member, a ring having external gear teeth abutting against one face of said enlargement, bolt and nut assemblies for holding said gear ring in position, a rotatable ring, and a flange on said enlargement for holding said rotatable ring against lateral movement in one direction, said gear ring limiting lateral movement of said rotatable ring in the opposite direction.

2. Driving mechanism for a digging wheel provided with a pair of laterally spaced annuli bridged by a series of excavating buckets, each annulus having laterally extending gear teeth, said mechanism comprising a gear for each annulus progressively engageable with the gear teeth thereof, and an independently rotatable roller associated with each gear and in rolling contact with the inner surface of the adjacent annulus.

3. Driving mechanism for a digging wheel provided with a pair of laterally spaced annuli bridged by a series of excavating buckets, each annulus having laterally extending gear teeth, said mechanism comprising a gear for each annulus progressively engageable with the gear teeth thereof, and a roller coaxial with the adjacent gear and rotatable independently thereof and engageable with the inner surface of the respective annulus.

4. Driving mechanism for a digging wheel provided with a pair of laterally spaced annuli bridged by a series of excavating buckets, each annulus having laterally extending gear teeth, said mechanism comprising a gear for each an-

nulus progressively engageable with the gear teeth thereof, a ring coaxial with each gear and in rolling contact with the under surface of the respective annulus, and means for mounting each ring to enable rotative movements thereof independently of the adjacent gear.

5. A driving gear assembly for a digging wheel comprising a hub member, a shouldered portion on said hub member, a ring having external gear teeth abutting said shouldered portion, fasteners for holding said gear ring in position, a rotatable ring on said shouldered portion limited from lateral movement in one direction by said gear ring, and means on said shouldered portion for limiting lateral movement of said rotatable ring in the opposite direction.

6. A driving gear assembly for a digging wheel having an annulus provided with laterally extending gear teeth, said gear assembly comprising a hub member, a ring having external gear teeth mounted on said hub member, the teeth on said ring being adapted to mesh progressively with the gear teeth on the digging wheel annulus, means for connecting said ring to said hub member, and a second ring coaxial with said gear ring and independently rotatable on said hub member for rolling contact with the inner surface of the digging wheel annulus.

7. A driving gear assembly for a digging wheel having an annulus provided with laterally extending gear teeth, said gear assembly comprising a hub member, a ring having external gear teeth mounted on said hub member, the teeth on said ring being adapted to mesh progressively with the gear teeth on the digging wheel annulus, means for connecting said gear ring to said hub member, a lateral extension on said hub member, a second ring rotatable on said extension for rolling contact with the inner surface of the digging wheel annulus, and means for holding said second ring from lateral movement.

HUBERT HOLLMANN.
